PORTABLE SUPPORT FOR PUNCHING BAGS

Leonard F. Ross, Philadelphia, Pa.

Application April 21, 1953, Serial No. 350,117

1 Claim. (Cl. 272—78)

1

My invention relates to a portable and adjustable support for a punching bag.

The object of the invention is to produce an improved support which is rigid and relatively inexpensive and one which can be adjustably mounted on a horizontal or on a vertical support.

The full nature of the invention will be understood from the following specification and the accompanying drawing in which:

Fig. 1 is a perspective view showing my improved support applied to a door jamb.

Fig. 2 is a perspective view showing my improved support applied to a horizontal support.

Fig. 3 is a sectional view looking in the direction of line 3—3 on Fig. 1.

Fig. 4 is a sectional view looking in the direction of line 4—4 on Fig. 2.

Fig. 5 is a sectional view looking in the direction of line 5—5 on Fig. 4.

The support includes a rod one portion 12 of which is threaded and the other portion 14 of which is unthreaded. The threaded portion 12 has a smaller diameter than the unthreaded portion 14 whereby a shoulder 16 is formed, and is provided with a flat surface 18. The end of unthreaded portion 14 is reduced to form a smooth, unthreaded hub 20 which is again reduced to form a threaded portion 22.

The support further includes a pair of plates 24 and 26 which are adapted to engage, therebetween, a horizontal table, shelf, or the like 28, as in Figs. 2 and 4, or a vertical porch column or the vertical jamb of a door, or the like, 30. Each of the plates 24 and 26 is provided with an opening 32 which is also provided with a flat surface 34 (Fig. 5) which corresponds to the flat surface 18 of rod portion 12. The openings 32 are such that the plates 24 and 26 can slide freely on threaded rod portion 12.

The hub 20 is adapted to support a rotatable member 36 which is freely rotatable on this hub and which is retained in position by a nut or the like 40. The collar 36 is provided with a hole 38 adapted to be detachably engaged by a snap hook carried by a punch bag 41. To clamp plate 26 against the support 28 or 30, I provide a threaded nut 42 which is preferably provided with a handle 44.

To set up the support so that the punch bag will rotate about a vertical axis, as in Figs. 2 and 4, the plate 26 is moved up on threaded rod portion 12 until it abuts shoulder 16. The device

2

is now presented to the edge of a horizontal support 28 and the plate 24 is brought to rest on the upper face of said support. The plate 26 is next slipped over the rod portion 12 and the nut 44 is threaded onto rod portion 12 and rotated until it abuts the underside of plate 26 and presses it upwardly against the support 28 and the upper plate 24. The punching bag is then detachably engaged with collar 36 by means of a hook, not shown, which is carried by the bag. When the bag is punched it will rotate about the vertical axis of the rod as shown in Fig. 4.

To set up the stand so that the bag will rotate about a horizontal axis, the plates 24 and 26 are similarly clamped onto the vertical jamb of a door or onto a partition, or vertical porch column, or the like, at a height suitable to the party who wishes to use it. The bag thus mounted will rotate about the horizontal axis of the rod as viewed in Fig. 3.

To provide a better grip and to guard against damaging the surface of the support, the engaging sides of plates 24 and 26 are provided with felt or rubber linings 46.

25 What I claim is:

A portable support for a punching bag, said support including a rod having one portion thereof threaded and the other portion thereof unthreaded, said unthreaded portion being of a larger diameter whereby a shoulder is formed at the junction of said portions, said threaded portion having a flat surface portion extending lengthwise thereof, a pair of clamping plates adapted to clamp a horizontal or a vertical support therebetween, each of said plates having an opening therein of the same shape as said threaded portion and freely slidably thereon, said opening being too small for the passage of said shoulder therethrough, a nut engageable with said threaded portion for urging said plates and the support therebetween against said shoulder, and a collar freely rotatable on said unthreaded portion and having a hole formed therein adapted to be engaged by hook on the punch bag.
